UNITED STATES PATENT OFFICE

169,482

DISPLAY UNIT OF INTERFITTED TOY
BLOCKS

Jane B. Henke, near Seattle, and Robert W. Beach, Seattle, Wash.; said Beach assignor to said Henke

Application September 18, 1951, Serial No. 16,675

Term of patent 14 years

(Cl. D34—15)

To all whom it may concern:

Be it known that we, Jane B. Henke, a citizen of the United States and residing near Seattle, in the county of King and State of Washington, and Robert W. Beach, a citizen of the United States, residing at Seattle, King County, Washington, have invented a new, original, and ornamental Design for a Display Unit of Interfitted Toy Blocks, of which the following is a specification, reference being had to the accompanying drawings, forming a part hereof.

Figure 1 is a plan view of a display unit of interfitted toy blocks, showing our new design.

Figure 2 is an edge view thereof.

Figure 3 is a top isometric view thereof.

We claim:

The ornamental design for a display unit of interfitted toy blocks, substantially as shown.

JANE B. HENKE.

ROBERT W. BEACH.
